United States Patent Office

Des. 219,946
Patented Feb. 16, 1971

219,946

BILLBOARD

Carl A. Birnberg, 1641 Ford Parkway, and Henry S. Kristal, 1855 Pinehurst Ave., both of St. Paul, Minn. 55116

Filed Mar. 14, 1969, Ser. No. 16,240

Term of patent 14 years

Int. Cl. D20—03

U.S. Cl. D95—12

FIG. 1 is a front perspective view embodying our new design, and

FIG. 2 is an end elevation of the same.

The sign is shaded in FIG. 1 to indicate a contrasting color.

We claim:

The ornamental design for a billboard, as shown and described.
